UNITED STATES PATENT OFFICE.

FRANK GERBER, OF NEW YORK, N. Y.

FAN ATTACHMENT FOR SEWING-MACHINES.

SPECIFICATION forming part of Letters Patent No. 738,429, dated September 8, 1903.

Application filed May 25, 1903. Serial No. 158,610. (No model.)

To all whom it may concern:-

Be it known that I, FRANK GERBER, a subject of the Emperor of Austria-Hungary, residing at New York, in the county of New York and State of New York, have invented certain new and useful Improvements in Fan Attachments for Sewing-Machines, of which the following is a specification, such as will enable those skilled in the art to which it appertains to make and use the same.

The object of this invention is to provide a fan attachment for sewing-machines which is easily connected with sewing-machines of any construction and which may readily be removed or placed out of the way when the said attachment is not needed, a further object being to provide a fan attachment of the class hereinafter described and claimed which may quickly be adjusted to any desired position and which may also be connected with steam-operated machines without the necessity of affixing any additional parts to said sewing-machine.

My invention is fully described in the following specification, of which the accompanying drawing forms a part, suitable reference characters being employed to indicate the several parts thereof.

In the drawing forming part of this specification I have shown at *a* a portion of the operating-table of an ordinary foot-operated sewing-machine upon which is mounted the usual arm *b*, said arm being also provided with the usual fly-wheel *b*², upon which is mounted a pulley *b*³ of the usual construction and with which is connected the usual belt *b*⁴, which is in turn connected with the drive-wheel of the machine in the usual manner.

In practice I secure a plate *c* upon the top of the operating-table *a* and to the rear of the arm *b* and fly-wheel *b*², as clearly shown, and directly over the plate *c* and hinged thereto, as shown at *c*², is a supplemental plate *c*³, to which are secured two upwardly-directed stanchions *c*⁴ and *c*⁵, which support a top member *c*⁶, secured thereto, and passing through the supplemental plate *c*³ and into the plate *c* is a set-screw *c*⁷, which serves to hold the supplemental plate *c*³ to the plate *c*. The top member *c*⁶ acts as a guide for a vertical shaft *d*, which is free to revolve therein and in the supplemental plate *c*³, which serves as

the other guide therefor, and mounted on the shaft *d* are two bevel gear-wheels *d*² and *d*³, the lower of which, *d*³, is secured permanently to said shaft, while the upper of which, *d*², is slidably mounted on said shaft and adapted to be secured thereto at any point by means of a set-screw *d*⁴. Engaging the bevel gear-wheel *d*³ is a similar bevel gear-wheel *e*, which is secured to a longitudinally-arranged shaft *e*², passing through and supported by the stanchions *c*⁴ and *c*⁵, and said shaft *e*² is free to turn in said supports and is provided at a point between said stanchions with a pulley *e*³, with which is connected an endless belt *e*⁴, which also engages with the button *e*⁵ on the fly-wheel *b*², said button being common to all sewing-machines having a fly-wheel mounted on the arm thereof, and when the machine is being operated the shaft *e*² is also being turned, as well as the shaft *d*, as will be readily understood.

Connected with the top and bottom of the vertical shaft *d* and free to revolve thereon are two yoke-shaped arms *f* and *f*², and secured thereto and forming a frame therewith are two vertical rods *f*³ and *f*⁴, said rods serving as guides for a vertically-movable frame *h*, adapted to be secured at any point on said rods by means of set-screws *h*². The frame *h* consists of a transverse inner plate *h*³, provided with openings *h*⁴. Through said rods pass, an outwardly-directed tube *h*⁵, secured to each end of the plate *h*³, and a transverse outer plate *h*⁶, secured to the outer ends of said tubes, and arranged centrally of and loosely mounted in the transverse plates *h*³ and *h*⁶ is a shaft *i*, the portion *i*² of which between the said plates *h*³ and *h*⁶ is tubular and is provided with a longitudinal slot *i*³, through which passes a set-screw *i*⁴, which is held in a rod *i*⁵, slidably mounted in the tube *i*², and on the outer end of the rod *i*⁵ is a bevel gear-wheel *i*⁶, while on the inner end of the shaft *i* is another bevel gear-wheel *i*⁷, which is engaged by the bevel gear-wheel *d*² on the vertical shaft *d*. Slidably mounted in each of the tubes *h*⁵ is a rod *k*, the outer ends of said rods *k* being secured to a frame *k*², comprising side members *k*³ and transverse end members *k*⁴ and *k*⁵, to the member *k*⁴ of which the rods *k* are connected, and the shaft member *i*⁵ passes through the end member *k*⁴ of the frame *k*², the bevel

gear-wheel i^6 thereof being within said frame and engaging with a similar bevel gear-wheel m , firmly connected with a transversely-arranged shaft m^2 , which is loosely mounted in the side members k^3 of the frame k , and secured to the end of the shaft m^2 , adjacent to the arm b of the machine, is a fan n of the usual or any desired shape, and, as will be seen, when the fly-wheel b^2 is operated the fan n will also be operated by means of the shafts e^2 , d , and i and the gear-wheels mounted thereon, the speed of the fan n depending upon the speed of the fly-wheel b^2 .

When it is desired to dispense with the fan temporarily, the set-screw c^7 is released and the supplemental plate c^3 and all the mechanism connected therewith is thrown back into the position shown in dotted lines, and if it is desired to raise the same higher all that is necessary is to release the set-screws h^2 of the frame h , as well as the set-screw d^4 of the bevel gear-wheel d^2 , place the fan at the desired height, and tighten the said set-screws.

It will be understood that the belt e^4 is thrown off when the fan and mechanism thereof is thrown back out of the way, and the frame h and that formed by the yoke-shaped arms f and f^2 may be swung on the pivotal point of the said arms, and as the center thereof is the shaft d the bevel gear-wheels d^2 and i^7 will always engage, and by means of this construction air may be sent in any desired direction, the friction between the arms f and f^2 with the top member c^6 and the plate c^3 being sufficient to hold the said fan and frames in any desired radial position.

Although I have shown my fan attachment connected with a foot-operated sewing-machine, it will be evident that the same may be connected with the power-shaft of a steam-operated machine by merely changing the position of the belt b^4 , and various other changes in and modifications of the construction herein shown and described may be made without departing from the spirit of my invention or sacrificing its advantages.

Having fully described my invention, what I claim as new, and desire to secure by Letters Patent, is—

50 1. A fan attachment for sewing-machines, comprising a plate detachably secured to the operating-table of said machine, a supplemental plate hinged thereto, a plurality of stanchions on said supplemental plate, a horizontal plate secured to the top of said stan-

chions, a frame pivotally mounted between said horizontal and supplemental plates, supplemental frames carried by said first-named frame, a fan rotatably mounted in one of said supplemental frames and means for operating said fan, substantially as shown and described. 60

2. A fan attachment for sewing-machines, comprising a base-plate, a support mounted thereon, a pivoted frame on said support, a vertically-movable frame on said pivoted frame, a rod slidably mounted in each of the side members of said vertically-movable frame, a supplemental frame secured to the outer ends of said rods, a fan mounted on 65 said supplemental frame, and means connected with said sewing-machine for operating said fan, substantially as described. 70

3. A fan attachment for sewing-machines, comprising a base-plate, a support mounted 75 thereon, a pivoted frame in said support, a vertically-movable frame on said pivoted frame, a longitudinally-movable frame mounted in said vertically-movable frame, a shaft passing through said longitudinally-movable frame, a fan on the outer end of said shaft, a bevel gear-wheel on said shaft, a telescopic shaft in said vertically-movable frame consisting of a tube and a rod mounted therein, a bevel gear-wheel on said rod and engaging said first-named bevel gear-wheel, a supplemental bevel gear-wheel on the inner end of said tube, a vertical shaft on said base-plate and said support, a bevel gear-wheel on said vertical shaft, a supplemental bevel gear-wheel, 80 adjustably mounted on said vertical shaft and engaging the bevel gear-wheel on said tube, a horizontally-arranged shaft in said support, a bevel gear-wheel on the end of said last-named shaft, said bevel gear-wheel engaging the first-named bevel gear-wheel on said vertical shaft, a pulley on said horizontally-arranged shaft in said support, 85 and means for connecting said pulley with a rotatable member of said sewing-machine, 90 substantially as shown and described. 95

In testimony that I claim the foregoing as my invention I have signed my name, in presence of the subscribing witnesses, this 22d day of May, 1903.

FRANK GERBER. [L. S.]
